ELECTROMAGNETIC TIMING RELAY

Theodore F. Rosing, Whitefish Bay, and Edwin W. Seeger, Wauwatosa, Wis., assignors to Cutler-Hammer, Inc., Milwaukee, Wis., a corporation of Delaware

Application November 7, 1943, Serial No. 627,261

4 Claims. (CL 175—320)

1

The invention relates to a timing relay and is particularly applicable to a relay which is adapted to respond selectively in accordance with the lapse of time after initiation of commutation of the energizing current.

It is often desirable to provide relay means for the control of two succeeding functions with a time interval between the two functions.

An object of the present invention is to provide a relay having an oscillating element with means to move the latter in one direction upon simultaneous energization of two electromagnets connected in series with each other and to thereafter cause the oscillating element to move in the opposite direction after a given interval of time following the initial movement.

Another object is to provide a balanced electromagnetic relay with two series connected magnets having different pulls and adapted to normally operate the relay in one direction, but reversing the direction of operation as a function of the commutation of the energizing current.

Another object is to provide a relay of the aforementioned kind which upon energization will close a circuit and a given time thereafter reopen said circuit and close and maintain closed an alternative circuit.

Another object is to provide a relay, the time of response of which is not appreciably affected by the voltage of the energizing current.

Other objects and advantages will hereinafter appear.

The accompanying drawing illustrates a relay embodying the invention.

In the drawing,

Figure 1 is a diagrammatic showing of a relay with the associated power supply and control instrumentalities.

Fig. 2 shows the pull of the relay coils as a function of the energizing current.

Fig. 3 shows the current in the different branches of the energizing circuit upon closure of the circuit as a function of elapsed time after closure for two values of the supply voltage, while

Fig. 4 shows the relation between the pull of the two coils as a function of elapsed time after closure.

The system shown in Fig. 1 embodies a relay 8, which may be energized from the bus bars 1, L² of a direct current power supply, the energizing current being controlled by a switch 11. The relay has a lever 12, the center of which is pivotally supported by a stationary pivot 13. Each end of the lever 12 is provided with a mag-

2

netizable armature 14 and 15, respectively. The lever is normally biased to its center position by a centering spring 16. Attached to the lever is also a movable contact arm 17, arranged to operate with stationary contacts 18 and 19, respectively, upon rotation of the lever in opposite directions.

A magnetizing coil 20 of relatively low resistance and low inductance cooperates with the armature 14, tending when magnetized, to attract the latter, and a magnetizing coil 21 of relatively high resistance and relatively low inductance, but higher than that of coil 20, cooperates similarly with the armature 15. A condenser 22 is connected in shunt with the coil 21. The tractive force of the two coils upon their respective armatures is such, that with the same current flowing through the two coils, the pull of the coil 21 exceeds that of the coil 20 and rotates the lever in a clockwise direction to cause engagement of contacts 17 and 18.

When the switch 11 is open the relay lever is in the position shown. Upon closure of the switch current flows from line L¹, through switch 25 11, coils 20 and 21 to line L². A part of the current by-passes the coil 21 through the condenser 22 to charge the latter. Hence, during the initial rise of the current to its final value, the ratio of energization of the coil 21 is less relative to that 30 of coil 20, than that obtaining when the current is constant, the ratio referred to decreasing with increasing charge of the condenser 22, thereby deflecting an increasingly greater portion of the total current through the coil 21, until the pull 35 of the coil 21 is greater than that of coil 20. Thereupon the lever is revolved clockwise to disengage the contacts 17 and 18 and engage the contacts 17 and 19.

As aforesigned, the diagram, Fig. 2, shows the 40 pulls of the coils 20 and 21, respectively, for different steady currents flowing through the respective coils.

Fig. 3 shows the current in the various parts of the circuit as a function of the time elapsed after 45 its completion. The curves I²⁰, I²¹, and I²² are the currents in the coils 20 and 21 and the condenser 22, respectively, at various intervals after the closure of the control switch for a given line voltage, resulting in a given steady current after the 50 transient period. If the voltage of the supply circuit is reduced to two-thirds, the currents in the aforementioned elements are reduced to two-thirds of the former values, as shown by curves I'²⁰, I'²¹ and I'²², respectively. Fig. 4 shows the 55 pull of the two magnets in relation to the elapsed

time after completion of the circuit. The pull curves P^{20} and P^{21} again refer to a given line voltage, while the pull curves P'^{20} and P'^{21} show the respective pulls for substantially two-thirds of the aforementioned line voltage. It will be seen from Fig. 4 that for either voltage the pull of the coil 20 predominates over that of the coil 21 prior to the moment indicated by A in the diagram and it will also be apparent that the interval from the time of closure of the circuit to the moment A changes little with variations of the supply voltage.

It will also be apparent from the foregoing that the response of the relay is also subject to elapsed time upon opening of the circuit.

Thus if the contacts 17 and 18 are engaged while current is flowing through the windings or even when under this condition the pulls of the two coils are equal and the relay is in its center position and the current is interrupted, the charged condenser discharges through the coil 21, thereby temporarily maintaining its current above the value of the decaying line current passing through coil 20. The resulting clockwise torque tends to rotate the relay to complete the circuit between contacts 17 and 18 or maintain this circuit for a time dependent upon the capacity of the condenser 22 and of the inductance of the coil 21.

We claim:

1. In a timing system, a relay comprising an oscillatable armature normally biased to a neutral position, a pair of direct current electromagnets acting upon said armature and tending to move it in opposite directions respectively, the windings of said electromagnets being connected in series with each other for normally passing the same energizing current therethrough, said electromagnets being so constructed and calibrated that the operating effect of one of the same upon said armature for any given current exceeds the effect of the other, and means electrically connected in parallel with the winding of said one of said electromagnets to delay the rate of change of the current therein relative to the rate of change of said energizing current upon transient changes thereof.

2. In a timing system, a relay comprising an oscillatable armature normally biased to a neutral position, a pair of direct current electromagnets acting upon said armature and tending to move it in opposite directions respectively, the windings of said electromagnets being connected in series with each other for normally passing the same energizing current therethrough, said electromagnets being so constructed and calibrated

that the operating effect of one of the same upon said armature for any given current exceeds the effect of the other, and means electrically connected in parallel with the winding of one of said electromagnets to delay the rate of change of the current therein relative to the rate of change of said energizing current upon transient changes thereof.

3. In a timing system, a relay comprising an oscillatable armature normally biased to a neutral position, a pair of direct current electromagnets acting upon said armature and tending to move it in opposite directions respectively, the windings of said electromagnets being connected in series with each other for normally passing the same energizing current therethrough, said electromagnets being so constructed and calibrated that the operating effect of one of the same upon said armature for any given current exceeds the effect of the other, and a condenser connected in parallel with the winding of said one of said electromagnets to delay the rate of change of the current therein relative to the rate of change of said energizing current upon transient changes thereof.

4. In a timing system, a relay comprising an oscillatable armature normally biased to a neutral position, means operated by said armature for selectively commutating an electric circuit upon movement of said armature from said neutral position, a pair of direct current electromagnets acting upon said armature and tending to move it in opposite directions respectively, the windings of said electromagnets being connected in series with each other for normally passing the same energizing current therethrough, said electromagnets being so constructed and calibrated that the operating effect of one of the same upon said armature for any given current exceeds the effect of the other, and a capacitor connected in parallel with the winding of said one of said electromagnets to delay the rate of change of the current therein relative to the rate of change of said energizing current upon transient changes thereof.
